B. BOLTON,
AMPLIFIER FOR PHONOGRAHS,
APPLICATION FILED OCT. 23, 1919.

1,372,269.

Patented Mar. 22, 1921.

UNITED STATES PATENT OFFICE.

BENJAMIN BOLTON, OF SALT LAKE CITY, UTAH.

AMPLIFIER FOR PHONOGRAFS.

1,372,269.

Specification of Letters Patent. Patented Mar. 22, 1921.

Application filed October 23, 1919. Serial No. 332,609.

To all whom it may concern:

Be it known that I, BENJAMIN BOLTON, a subject of the King of England, residing at Salt Lake City, in the county of Salt Lake and State of Utah, have invented certain new and useful Improvements in Amplifiers for Phonographs, of which the following is a specification.

This invention relates to amplifiers or more particularly to horns used upon any of the many approved types of gramophones, and an object of the invention is to provide a horn which will carry and magnify the music or sound reproduced by a mechanism reproducer, and one which will be free from any metallic sounds, resulting in the reproducing of clear lifelike notes and sounds.

It is a well known fact that in even the most expensive gramophones of approved type now in use, there is more or less metallic sound to the music which is reproduced and transmitted through a metal horn, the action of the metal in the horn often distorting and destroying some of the most beautiful notes reproduced, and it is an object of this invention to provide a horn or sounding board structure which is entirely free from any metal in its construction, being constructed of plastic material, reinforced by fabric and wood, so as to provide a comparatively rigid unbreakable reproducing horn in which the ill effects of metal are entirely eliminated as well as one which will reproduce the finest notes or sounds in their true state.

Other objects of the invention will appear in the following detailed description taken in connection with the accompanying drawings, forming a part of this specification and in which drawing:

Figure 1 is a side elevation, partly in section, of a horn constructed in accordance with this invention.

Fig. 2 is a cross section taken on the line 2-2 of Fig. 1.

Fig. 3 is a section on the line 3-3 of Fig. 1.

Referring more particularly to the drawings, wherein like characters indicate like and corresponding parts throughout the several views, the improved horn or sound board 10 may be constructed in any desired shape, without departing from the spirit of this invention, and it is composed of superposed layers of plastic material and fabric

having a layer 11 of plastic material, at the interior thereof, against the outer surface of which the fabric layer 12 is placed. This layer 12 may be of canvas, burlap or any analogous fabric, and prior to placing it upon the inner layer 11, it is preferably impregnated with liquid plastic material and adhesive, such as liquid plaster of Paris and glue. To reinforce and brace the horn structure 10, a plurality of bracing strips 13 of wood, preferably pine, are placed upon the outer surface of the fabric layer 12 at circumferentially spaced points, and they extend longitudinally of the horn structure, serving to reinforce the same and prevent accidental breaking of any part thereof. Fabric strips 14 are placed over the outer surfaces of the strip 13 and the coating of plastic material 14' is then placed over the outer surface of the fabric layer 12, and fabric strips 14', entirely inclosing these portions of the horn structure.

The L neck 15, of the horn structure is made up of an inner layer 16 of plastic material, an intermediate layer 17 of fabric, an outer layer 18 of plastic material preferably impregnated with glue or analogous adhesive, and as shown in Fig. 3 of the drawings, it is necessary to make this portion of the horn in sections, and at times it may be necessary to make the entire horn in sections depending upon the configuration thereof, and when the entire horn is made in section, the adjacent or facing edges of the horn are placed in engagement with each other, after the outer plastic layer 18 has been properly and set or hardened, after which strips 19 of fabric are placed over the meeting edges of the sections and a layer of coating 20 of the plastic material impregnated with glue is then placed over the strips 19 and the layer 18 of plastic material, thoroughly welding the sections of the horn or sounding board in properly connected position.

In constructing the horn, or sounding board, the following method is carried out. A mold of the shape in which the horn or sounding board is to be made is provided, and this mold is first coated, with a coating of liquid plastic material preferably plaster of Paris, which is mixed with water or any other suitable liquid to substantially the consistency of cream. However, prior to the coating of the mold, it is oiled or greased, so that the cast when set or hard-

2

ened will easily come off or free from the mold. The semi-liquid plastic material is placed over the mold, preferably with a brush, so as to evenly distribute this plastic material over the entire surface of the mold. After the mold is coated with the plastic material of substantially the consistency of cream, a second quantity of plastic material is made, which comprises a suitable quantity of plaster of Paris, or analogous plastic material which is moistened and mixed to a semi-liquid state, by half a tea-cup full of glue water, to each quart of pure water used in the mixing. The glue water is made from four ounces of powdered glue to one quart of water, or in such proportion, depending upon the quantity made. From the plaster of Paris or analogous plastic material, mixed with the adhesive, the semi-liquid plastic material is provided, with which a second coat or layer is put upon the mold, over the first coat, after this first coat has started to harden or set. However, care should be taken to apply this second layer or coat of plastic material impregnated with adhesive, before the first coat becomes thoroughly hardened, otherwise, they will not properly co-mingle to form the innermost portion of the sounding board or horn, etc. This second coat or layer should be put upon the first layer by a brush of the type used in cleaning and sufficiently to provide a relatively thin, even layer, thereof, after which the layer of fabric, such as burlap, canvas, or analogous material which has previously been cut to the shape wanted is dipped in the semi-liquid mixture of plastic material and adhesive and it is then placed over the mold about the coats of adhesive material and plastic material and smoothed out to lie flat thereover. Strips of pine wood, are then placed at the desired position circumferentially of the horn structure, and extend longitudinally thereover. After the strips of wood, preferably pine or analogous soft wood have been placed, strips of fabric, such as burlap, canvas or the like, which have been impregnated with the mixture of plastic material and adhesive, are placed over the outer surfaces of the longitudinally extending wood bracing strips and a layer of the admixed plastic material and adhesive is then put over these fabric strips and the portions of the first fabric strips which are still exposed to the desired thickness so as to thoroughly weld the fabric strips which cover the wood strips to the layer of fabric and draw the various parts of the horn or sounding board structure together, forming a unitary structure, which when hardened or set is removed from the mold. In making a horn or sounding board in sections, the joints are wrapped or covered with strips of canvas or analogous fabric which

has been previously impregnated with the admixed plastic material and adhesive, after which this fabric is coated over with a coating or layer of the admixed plastic material and adhesive, thoroughly welding the various parts or sections of the sounding board or horn structure. 70

While in the drawings, a horn, such as designed for use on an approved type of gramophone is shown, it is to be understood that sounding boards may be made for 75 lining music rooms in accordance with the above method, the bodies of the various types of instruments, such as the violins, may be made according to this method, so as to 80 provide sounding boards which are free from any metallic sound, and which will reproduce or transmit sounds or notes in their true state.

The plastic material is what is known as 85 a "dead" material, however, when it is employed in connection with the fabric and adhesive, a very live sound deflecting or carrying board is provided, which will revibrate or transmit the minutest sound or note, in 90 increased volume and its true tone, as well as a sound board which will not synchronize with the vibrations of the diaphragm of a gramophone, and consequently will not produce the metallic sound reproduced by machines of approved types using metal horns, especially in cases where high instrumental 95 notes are reproduced.

Changes in details may be made without departing from the spirit of this invention, 100 but;

I claim:

1. As a new article of manufacture, a sound horn for gramophones, comprising a layer of plastic material, a layer of admixed 105 plastic material and adhesive, and a layer of fabric.

2. As a new article of manufacture, a sound horn for gramophones composed of plastic material, fabric and reinforcing 110 strips of wood.

3. As a new article of manufacture, a sound horn for gramophones composed of a layer of plastic material, a layer of admixed plastic material and adhesive, a layer of fabric, 115 and a layer of admixed plastic material and adhesive upon said fabric layer.

4. As a new article of manufacture, a sound horn for gramophones composed of a layer of plastic material, a layer of admixed plastic material and adhesive, a layer of fabric, longitudinally extending bracing strips of wood upon said fabric layer, and a coating of admixed adhesive and plastic material upon said bracing strips and fabric layer. 120

5. As a new article of manufacture, a sound horn for gramophones composed of a layer of plaster of Paris, a second layer of admixed plaster of Paris and glue, a layer of fabric upon said admixed layer, 125

and a layer of admixed plaster of Paris and glue upon said fabric layer.

6. As a new article of manufacture, a sound horn for gramophones composed of 5 plaster of Paris, admixed plaster of Paris and glue, and fabric.

7. As a new article of manufacture, a sound horn for gramophones composed of 10 a plurality of sections, each of said sections composed of superposed layers of plastic material, admixed plastic material and adhesive, and fabric, and strips of fabric placed over the joints of the sections, said 15 connecting fabric strips covered with admixed plastic material and adhesive.

8. That method of making sounding 20 horns for gramophones which consists in first coating a mold with liquid plastic material, coating the resulting article with admixed plastic material and liquid adhesive, placing a layer of reinforcing fabric over the coating of admixed plastic material and adhesive, and placing a layer of finishing material over the said fabric layer.

25 9. That method of making sounding horns for gramophones which consists in first coating a mold with liquid plastic material, coating the resulting article with admixed plastic material and liquid adhesive, 30 and placing a layer of reinforcing fabric over the coating of admixed plastic material and adhesive, and placing a layer of admixed plastic material and adhesive upon said fabric layer.

10. That method of making sounding 35 horns for gramophones which consists in coating a mold with liquefied plastic material, coating the resulting article with admixed plastic material and liquid adhesive, placing a layer of reinforcing fabric over the coating 40 of admixed plastic material and adhesive, placing reinforcing strips of wood upon said fabric layer, and placing a layer of finishing material over the reinforcing wooden strips and fabric. 45

11. That method of making sounding 50 horns for gramophones which consists in coating a mold with liquefied plastic material, coating the resulting article with admixed plastic material and liquid adhesive, placing a layer of reinforcing fabric over the coating 55 of admixed plastic material and adhesive, placing reinforcing strips of wood upon said fabric layer, placing strips of fabric over said reinforcing strips, and coating said strips of fabric and fabric layer with an admixture of plastic material and adhesive.

12. That method of making sounding 60 horns for gramophones which consists in first coating the mold with liquefied plastic material, coating the resulting article with an admixed plastic material and liquid adhesive, placing a reinforcing element on said admixed plastic material and liquid 65 adhesive and applying a finishing material to the said reinforcing element.

BENJAMIN BOLTON.
